UNITED STATES PATENT OFFICE.

HARRY H. SCHROYER, OF CHICAGO, ILLINOIS, ASSIGNOR TO THE ACME SUPPLY COMPANY, A CORPORATION OF ILLINOIS.

SASH-SPRING.

1,229,531.

Specification of Letters Patent. Patented June 12, 1917.

Application filed March 12, 1913. Serial No. 753,767.

To all whom it may concern:

Be it known that I, HARRY H. SCHROYER, a citizen of the United States, and a resident of the city of Chicago, in the county of Cook and State of Illinois, have invented certain new and useful Improvements in Sash-Springs; and I do hereby declare that the following is a full, clear, and exact description of the same, reference being had to the accompanying drawings, and to the numbers of reference marked thereon, which form a part of this specification.

It is an object of this invention to provide means insertible in the sliding sash of a window adapted to contact the fixed weather stripping means on the frame to maintain the complementary engaging means secured on the sash in close contact therewith.

It is also an object of this invention to provide a device adapted to be secured in practically any position in the stile of the window sash and affording means preventing rattling of the sash in the frame.

It is also an object of this invention to provide a device in which the actuating elements are inclosed within interfitting casings and thereby thoroughly protected.

It is also an object of this invention to provide a sliding member capable of slightly differential movement to enable the same to readily adapt itself to inequalities of an uneven surface.

It is also an object of this invention to provide a device in which the elements are retained in proper relation by means of a single removable pin.

It is furthermore an object of this invention to construct a device in which the slideable casing is capable of slight differential movement and is actuated by springs at each end thereof.

It is furthermore an object of this invention to provide a device in which all the elements thereof are loosely engaged therein and the whole maintained together by means of a single pin.

It is finally an object of this invention to provide a device constructed of simple metal stamping of durable construction, and which may be assembled and installed by persons not having previous experience with the same.

The invention (in a preferred form) consists in the matters hereinafter described and more fully pointed out and defined in the appended claims.

In the drawings:

Figure 1 is a vertical transverse section taken through a car window, the sashes of which are equipped with a device embodying the principles of my invention.

Fig. 2 is a transverse horizontal section taken on line 2—2 of Fig. 1, showing a construction of the window post and the relative position and operation of the sash frame.

Fig. 3 is a front elevation of a device shown attached to a window sash.

Fig. 4 is a vertical section on line 4—4 of Fig. 3.

Fig. 5 is a horizontal section on line 5—5 of Fig. 4.

As shown in the drawings:

Referring to Fig. 1, the reference numeral 1, designates an outer sliding sash of a car window, of which the inner sliding sash is denoted by the reference numeral 2. The window is provided with inner and outer transom lights 3 and 4, respectively, which are offset on each side of said sliding sashes 1 and 2, to permit the same to be raised upwardly between said transom lights when it is desired to open the window. The window post comprises a T bar 5, which has rigidly secured to the flanges thereof, inner 6 and outer channels 7, and 8, respectively, said channels being of unequal width so as to receive the extremities of a continuous jamb and cheek plate 8, therebetween.

As shown, the outer channel or cheek plate 7, is provided at the ends of its side flanges with laterally extending flanges 9, which engage in a suitable recess in the stiles of the outer sash 1. The recess in the outer sash 1, is provided by rabbeting the outer edge of the stile in a stepped manner, and securing therein and flush with the outer face of the stile, a small T bar or strip of metal 10.

The cheek plate 8 extends inwardly on each side, thereby affording the side walls and end wall of the window post. Said cheek plate is provided with longitudinally disposed parallel recesses in the side walls thereof, the walls of said recesses being acutely angled in converging relation, and as clearly shown in Fig. 2, the rear surface of the metal forming the bottom of the recesses 11, have secured thereto, by spot welding or otherwise, the Z bars 12, which are rigidly connected to the T bar 5.

Resilient metallic inner sash stops 13, are

shown engaged in the recesses 11, and stops 14, are likewise secured in recesses 15. Thus it is seen that the inner sash 2, slides between the stops 13, and 14, while the outer sash 1, slides between the stop 14, and the weather stop flange 9.

The sash spring is constructed as follows: 16 represents a casing member having an aperture in each side wall thereof and also 10 provided with laterally extending flanges 17, adapted to receive screws 18, therethrough for attachment. A cup member 19, is shown inverted in the casing 16, the outside dimensions of said cup member being 15 slightly less than the inside dimensions of said casing 16, to permit a small amount of differential movement of the cup member therein, and to insure easy sliding of the same. The depth of the cup member is a 20 trifle less than that of the casing member 16, so that the cup may be depressed within the casing flush with flanges 17, thereof. Said cup member is provided in the side walls thereof with transverse slots 20, which 25 are centrally positioned and adapted to correspond with the apertures in the side walls of the casing 16.

A small pin 21, is inserted through the apertures in the casing 16, and the slots 20, 30 of the cup member 19, to engage the cup member and casing together in sliding relation. For the purpose of normally pressing said cup member outwardly, spiral springs 22, are loosely engaged between said members at each end thereof, and in order 35 to maintain said springs in proper position, a channel shaped bridge member 23, is sprung within the cup member 19, and extends from the bottom thereof, to a point 40 flush with the edges of the side walls.

The operation is as follows:

As shown in the drawings, the device as 45 connected in the window sash is adapted to bear against the fixed weather stop flange 9, thereby thrusting the sliding sash inwardly and bringing the members 9 and 10, into close contact to effect a seal. Inasmuch as the cup member 19, is slightly 50 smaller than the interior of the casing 16, and is retained therein by the single pin 21, a small amount of pivotal movement is thereby afforded about said pin, and due 55 to the positioning of the springs at each end thereof, said cup member is adapted to assume differential positions. The amplitude 60 of movement of said cup members is of course limited by the length of the slot 20. As shown more particularly in Figs. 3 and 4, the ends and outer edges of the 65 cup member are rounded to facilitate operation of the device.

Of course, I am aware that details of construction and operation may be varied with-

out departing from the principles of my invention, and I therefore do not purpose 65 limiting the patent granted otherwise than necessitated by the prior art.

I claim as my invention:

1. In a device of the class described 70 loosely interfitting cup members one inverted within the other, one member apertured and the other slotted in both of the side walls of each thereof, a pin engaged in said apertures and slots to retain said members together, springs loosely engaged in 75 each end of said interfitting members, and a bridge member sprung within one of said cup members adapted to space said springs in proper relation.

2. In a device of the class described, 80 cup members, spiral springs, a pin holding said members engaged to one another, and means bridging said pin sprung within one of said members adapted to space said springs in proper relation.

3. In a device of the class described the combination with a window sash, of a cup member disposed longitudinally thereof and recessed therewith, another cup member inverted therewith and having a sliding relation therewith, said first mentioned cup member having apertures therein and said second mentioned cup member having slots 90 therein disposed to register with said apertures, a pin extending transversely through 95 said interfitting cup members engaged in the apertures of the one and also in the slots of the other of said cup members, spiral springs disposed at each end of said interfitting cup members bearing against each 100 thereof to normally impel the same apart, and a spacing member mounted within said second mentioned cup member to maintain said springs properly positioned with respect to one another.

4. In a device of the class described interfitting cup members, the one having slots 105 therein and the other having apertures therein, a pin extending transversely through said cup members engaging through 110 said respective slots and apertures to permit a simultaneous pivotal and sliding movement of one of said cup members with respect to the other, springs disposed within said cup members acting normally to resist pivotal and sliding movement therebetween, and means bridging said pin to hold 115 said springs in position.

In witness whereof I have hereunto subscribed my name in the presence of two 120 subscribing witnesses.

HARRY H. SCHROYER.
